MOLDED RUBBER FOOTBALL

Orville R. Martin, Greensburg, Pa., assignor to The General Tire & Rubber Company, Akron, Ohio, a corporation of Ohio

Application February 28, 1957, Serial No. 643,133

5 Claims. (Cl. 273—65)

The present invention relates to an improvement in rubber footballs and more particularly to a molded rubber football having projecting ribs between the lacing holes for locating and supporting the lacing.

This application is a continuation-in-part of my copending application, Serial No. 577,324, filed April 10, 1956, and since abandoned.

According to the invention, the football is provided with a pocket between the cover and carcass, parallel rows of lacing holes in the cover near the sides of said pocket and ribs between the lacing holes for supporting the longitudinal and transverse portions of the lacing. The football preferably is provided with a straight longitudinal rib parallel to and extending the length of the rows of holes for supporting the two longitudinal portions of the lacing and a series of short lateral ribs extending from the longitudinal rib to the holes for supporting the several transverse lacing portions. The lateral ribs project radially outwardly beyond the lacing-engaging outer surface of the longitudinal rib so as to provide recesses above the latter rib of a size to receive the two longitudinal portions of the lacing.

Since the liner of the football tends to assume a circular transverse cross section due to the pressure of the gases within the football, the lacings tend to bulge outwardly so that the cover of the football has an oblong transverse cross-section in the vicinity of the lacing. In order to eliminate this bulging of the football, it is preferable to provide reinforcing cords extending around the football substantially from one end of the football to the other, the adjacent wraps of the reinforcing cord being closely spaced and being radially outwardly of the pocket between the cover and the carcass. The longitudinal rib for supporting the lacings may be cut to permit access to said pocket for punching the lacing holes and for permitting lacing of the football. Such cutting severs the reinforcing cords extending around the pocket but this does not weaken the football substantially since these cords are anchored in the rubber and since the severed ends are held together by the lacing. The reinforcing cords, therefore, prevent bulging of the football in the vicinity of the lacing even though they are cut.

Objects of the present invention are to provide an improved rubber football of simple inexpensive construction and to provide improved means for positioning the lacing on the football.

Another object of the invention is to reinforce a rubber football and to prevent bulging of the football in the vicinity of the lacing.

Other objects, uses and advantages of the invention will become apparent to those skilled in the art from the following description and claims and from the drawings in which:

Figure 1 is a perspective view on a reduced scale of the laced football of the present invention;

Figure 2 is a fragmentary transverse vertical sectional view of the laced football taken substantially on the line 2—2 of Fig. 1 and on a larger scale;

2

Figure 3 is a fragmentary top view of the football of Figs. 1 and 2 with the lacing removed showing the lacing-supporting ribs of the present invention;

Figure 4 is a fragmentary longitudinal sectional view of the football taken substantially on the line 4—4 of Fig. 3 and on the same scale;

Figure 5 is a fragmentary longitudinal sectional view taken substantially on the line 5—5 of Fig. 3 and on the same scale;

Figure 6 is a fragmentary transverse vertical sectional view taken substantially on the line 6—6 of Fig. 3;

Figure 7 is a top plan view on a reduced scale showing the football of the present invention;

Figure 8 is an end view of the football of Fig. 7, on the same scale, with parts broken away and shown in transverse cross-section;

Figure 9 is a fragmentary transverse sectional view of an enlarged scale, taken substantially on the line 9—9 of Fig. 7; and

Figure 10 is an enlarged fragmentary longitudinal vertical sectional view taken substantially on the line 10—10 of Fig. 7.

Referring more particularly to the drawings, in which like parts are identified by the same numerals throughout the several views, Figs. 1 to 6 shows a molded rubber football 1 of integral laminated construction including an impervious inflatable elastic rubber innerwall 2, an elastic rubber outer wall or cover 3, a carcass 4 of rubberized fabric sandwiched between and bonded to the inner and outer walls 2 and 3 in the conventional manner, and a conventional inflating valve 5 extending through the three laminae to permit insertion of an inflating needle into the air chamber 6 within the bladder 2. The carcass 4 completely encloses the bladder 2, and the cover 3 completely encloses the carcass, the laminated wall formed by these elements being generally in the form of an ellipsoid of revolution as with conventional footballs.

The laminated wall is provided with a longitudinally elongated, generally rectangular pocket 7 midway between the ends of the football. Such pocket may be formed between the cover 3 and the carcass 4 in any suitable manner, for example as disclosed in U. S. Patent No. 2,693,224. A generally rectangular insert 8 in the form of a layer of elastic rubber or rubberized fabric of a size to cover the pocket 7 is preferably bonded to the cover 3 above said pocket to reinforce the portions 23 of the cover above the pocket. Additional layers may also be provided above and below the pocket, if desired.

The shape of the outer surface of the cover 3 is determined by the shape of the mold in which the rubber football is vulcanized. Such mold is provided with ridges which produce longitudinal grooves 9 in the outer surface of the football 1 to simulate the grooves at the seams of a conventional leather-covered football and, if desired, may be shaped to produce imitation stitching and imitation pebbling.

According to the present invention, the mold cavity is provided with lateral and longitudinal recesses so that the cover portions 23 of the football 1 are molded with a single wide straight longitudinal rib 10 of rectangular transverse cross section extending more than three-fourths the length of the pocket 7 and narrow lateral ribs 11 of the same size and shape extending from the opposite sides of the longitudinal ribs toward the sides of said pocket. Said ribs are located above the pocket 7 to provide a support for the lacing.

A layer of paper, fabric or other suitable separating material is placed between the carcass 4 and the cover 3 so that the pocket 7 will be formed when the football is vulcanized. After vulcanization the portion of the cover

3 above the separating layer, in which the ribs 10 and 11 are formed, is imperforate and completely covers the separating layer, the wide rib 10 being located substantially midway between the opposite sides of said layer. Said rib and the underlying insert 8 is then cut down the middle with a suitable knife or the like to form a straight slit 12 extending almost the full length of the wide rib 10, a V-shaped groove 13 preferably being provided midway between the opposite sides of said wide rib to facilitate the cutting. The slit 12 divides the wide rib 10 into two longitudinal rib portions 14 of the same size and permits removal of the separating layer in the pocket 7 between the insert 8 and the carcass 4. The slit also permits insertion of a punch or other suitable tool into the pocket 7 to cut holes in the cover portions 23 and permits lacing of the football.

As herein shown, circular holes 15 are punched at the opposite ends of the longitudinal rib 10, and two straight rows of circular holes 16 and 17 are punched on opposite sides of the rib 10 at the ends of the lateral ribs 11. The holes of each row are equally spaced and are longitudinally aligned with each other and laterally aligned with the holes of the other row as best shown in Fig. 3 which is drawn substantially to scale. The holes 16 and 17 are adapted to receive a conventional leather lacing 18 of rectangular cross section, and the holes 15 are large enough to receive two longitudinal portions of said lacing.

The football of the present invention may be laced in a conventional manner with a single piece of lacing 18 substantially as shown in Figs. 1 and 2. When the football is laced in this manner, the two straight longitudinal portions 19 of the lacing rest on top of the rib portions 14 on opposite sides of the slit 12 and the several transverse portions 20 of the lacing rest on top of the lateral ribs 11, which are preferably trianguloidal as best shown in Fig. 2. The rib portions 14 and the ribs 11 preferably have a width corresponding substantially to the width of the lacing 18 so that they are completely covered by the lacing. Each lateral rib 11 is integral with the adjacent longitudinal rib portion 14 and extends from said rib portion to the margin of a hole 16 or 17, said rib being laterally aligned with a rib 11 on the other side of the slit 12. A symmetrical rib arrangement shown herein, each of the holes 16 and 17 being located the same distance from the slit 12 and each of the lateral ribs 11 being of the same size.

The height of each rib 11 at the edge thereof nearest the slit 12 is greater than the height of the rib portions 14 by an amount corresponding substantially to the thickness of the lacing 18 so as to provide a rectangular recess 21 above the longitudinal rib 10 and between each pair of laterally aligned ribs 11. Each of the longitudinally aligned recesses 21 preferably has a height corresponding substantially to the height of the lacing 18 and a width equal to or slightly greater than twice the width of said lacing so that the longitudinal lacing portions 19 are securely held in place by the transverse lacing portions 20 and the vertical faces of the ribs 11 which are longitudinally aligned. The lateral ribs 11 are preferably rounded substantially as shown in Fig. 2 so that they engage and support the lacing portions 20 from the margins of the holes 16 and 17 to the marginal edges of the recesses 21. The rib portion 14 may have a height greater than the thickness of the lacing so that the lacing extends a substantial distance outwardly to facilitate gripping of the football during passing.

The rubber liner 2 of the football 1 tends to assume a circular internal transverse cross section in the neighborhood of the lacing and to cause the football to bulge outwardly on the lacing side. Football players prefer a football which does not bulge out at the lacing and which is constructed so that the lacing does not project too far beyond the general contour of the cover. Figures 7 to 10 show a preferred form of football 31 according to the present invention, having a reinforcing cord 30 of nylon,

rayon, or other suitable material wound around the football to provide a multiplicity of closely and evenly spaced wraps or convolutions 30a, extending substantially the length of the football.

5 The molded rubber football 31 is of an integral laminated construction and includes an impervious inflatable elastic rubber inner wall 32, an abrasion-resistant elastic rubber outer wall or cover 33, and a carcass 34 of rubber-impregnated fabric sandwiched between and bonded to the inner and outer walls 32 and 33. A conventional inflating valve 35 extends through the three laminae to permit insertion of an inflating needle into the closed air chamber 36 within the bladder 32. The carcass 34 completely encloses the bladder 32 and the cover 33 completely encloses said carcass. The laminated wall formed by these elements is generally in the form of an ellipsoid of revolution as shown in Figs. 7 and 8.

The laminated wall is provided with a longitudinal generally rectangular pocket 37 midway between the ends of the football, which is formed between the cover 33 and the carcass 34, like the pocket 7 of the first described football 1. A generally rectangular reinforcing layer 38 of rubberized fabric of a size to cover the pocket 37 is bonded to the cover 33 above said pocket to reinforce the portions 53 of the cover above the pocket. Additional layers of elastic rubber or rubberized fabric may be provided above and below the pocket.

As herein shown the football 31 is provided with a thin layer 38a of elastic rubber coextensive with the layer 38 and integrally bonded thereto radially outwardly of the pocket 37, and two generally rectangular layers 52 and 52a of the same size as the layers 38 and 38a are provided radially inwardly of the pocket 37. The layer 52 is formed of rubberized fabric and is bonded to the fabric carcass 34. The layer 52a is a thin layer of rubber similar to the layer 38a and bonded to the layer 52. The adjacent surfaces of the rubber layers 38a and 52a forming the pocket 37 do not stick together after the paper or cloth insert therebetween is removed. If desired such surfaces may be treated with a suitable parting material so that they cannot stick together.

The mold in which the rubber football is cured may be shaped so that the cover of the football has the appearance of leather. The mold may be provided with ridges which produce longitudinal grooves 39 in the outer surface of the football to simulate the seams of a conventional leather-covered football. The mold may also be shaped to produce imitation stitching and pebbling. The mold cavity is provided with lateral and longitudinal recesses so that the cover portions 53 are molded with a single straight wide longitudinal rib 40 of rectangular cross section extending more than three-fourths the length of the pocket 27 and narrow lateral ribs 41 of the same size and shape extending from the sides of the ribs 40 toward the marginal sides of said pocket.

It will be readily apparent, to those skilled in the art, from the above description how the football of the present invention may be made. A layer of paper, fabric, or other suitable separating material is placed between the carcass 34 and the cover 33 and remains in that position when the football is vulcanized. The reinforcing cord 30 is imbedded in the rubber of the cover layer 33 a small fraction of an inch below the outer surface of said cover layer and extends around the separating layer. After vulcanization the wide rib 40, which is located substantially midway between the opposite sides of the separating layer, and the underlaying layers 38 and 38a, is then cut down the middle with a suitable knife, or the like, to form a straight slit 42 extending almost the full length of the rib 40. A V-shaped groove 43 is provided midway between the sides of the rib 40 to facilitate the cutting. This cutting severs the reinforcing cord 30 so that the cut ends of this cord are exposed at the slit 42 as shown in Fig. 10. This slit divides the wide rib 40 into two longitudinal rib portions 44 of the same size and permits re-

moval of the separating layer whereby the pocket 7 is formed between the rubber layers 38a and 52a. The slit also permits insertion of a punch into the pocket 37 to cut circular holes in the cover portions 53, and permits lacing of the football.

The holes 45 are punched at the opposite ends of the longitudinal rib 40 and have a diameter equal to or slightly greater than the width of the lacing. The holes 46 and 47 are arranged in straight parallel rows on opposite sides of the rib 40 at the ends of the lateral ribs 41. The holes of each row are preferably equally spaced and are preferably longitudinally aligned with each other and laterally aligned with the holes of the other row, for example, as shown in Fig. 7. The holes 45, 46 and 47 are adapted to receive a conventional leather lace 48 of rectangular cross-section having a width not substantially greater than the diameter of the holes. The football 31 may be laced with a single piece of lacing 48 just like the football 1 of Figs. 1 to 6, whereby the two straight longitudinal portions 49 of the lacing rest on top of the rib portions 44, and the several transverse lacing portions 50 rest on the top surfaces of the lateral ribs 41 which have a trianguloidal shape as shown in Fig. 9.

The rib portions 44 and the ribs 41 may have a width corresponding substantially to the width of the lacing 48 so that they are completely covered by the lacing and are not noticeable as viewed in Fig. 7. Each lateral rib 41 is integral with the adjacent rib portion 44 and extends from said rib portion to the margin of a hole 46 or 47. Each lateral rib 41 is laterally aligned with a rib 41 on the opposite side of the slit 12, the ribs preferably being arranged in a symmetrical manner.

The height of each rib 41 at the side of the wide rib 40 is greater than the height of the rib portions 44 by an amount corresponding substantially to the thickness of the lacing 48 so as to provide a recess 21a of rectangular cross section between each pair of laterally aligned ribs 41 for receiving the longitudinal portions 49 of the lacing. Each of the recesses 21a preferably has a height corresponding substantially to that of the lacing 48 and a width corresponding substantially to twice the width of the lacing so that the longitudinal lacing portions 48 engage and are held securely in place by the transverse lacing portions 50 and the vertical faces of the ribs 41.

The lateral ribs 41 are generally triangular and preferably are aligned substantially as shown in Figure 9 so that they engage and support the lacing portions 50 from the margins of the holes 46 and 47 to the marginal edges of the recess 21a. As herein shown the rib portions 44 of the football 31 have a height not substantially greater than about .04" and not substantially greater than the thickness of the lacing 48. Such a height is preferred by most football players since it locates the lacing for proper gripping of the football.

Except for the height of the ribs of the football 31, the ribs and the lacing of said football are substantially the same as the ribs and lacing of the first described football 1. The reinforcing cord 30 causes the cover layer 33 to assume a substantially circular transverse cross section as indicated in Figs. 8 and 9 so that the inner layer of bladder 32 bulges inwardly away from the lacing against the pressure of the gases within the football. The lacing 48 holds the cut ends of the cord 30 together so that the cords prevent bulging of the portion 53 of the cover. The football 31, therefore, has a shape more nearly corresponding to a conventional leather-covered football than the first described football 1. Bulging of the football at the lacing is not prevented if reinforcing cord, similar to the cord 30, is provided radially inwardly of the lacing receiving pocket 7.

As is well known in the art, in making a football of the type described herein, the first step is to form a bladder and to partially inflate it to a size somewhat less than the desired size of the finished ball. A coating of a vulcanizable material, such as latex or rubber cement, then may be

applied to the bladder as by dipping, spraying, or other suitable method. Subsequently, a reinforcing layer may be applied to the coated bladder in the form of pieces of cross-woven fabric.

5 When making the football 1, the fabric reinforcing layer 4 is applied to the inflated bladder 2 to cover the bladder completely. The fabric has threads spaced far enough apart to permit slight changes in shape so that the fabric conforms to the shape of the bladder. If desired, additional reinforcing cords, similar to the cords 30 of the football 31, may be wrapped around the reinforcing layer 4. Thereafter, the separating layer 8 is applied against the layer 4. Another coating of rubber cement, or other vulcanizable rubber material, is then applied to the reinforcing layer 4 and the layer 8, and the cover layer 3 of abrasion-resistant elastic rubber is applied over the layers 4 and 8 to enclose completely the fabric portions of the football. The football is then placed in a suitable mold and is further inflated to press the cover layer 3 into intimate contact with the wall of the mold cavity, and to press the laminae 2, 3, 4 and 8 into intimate contact with each other, the mold being heated to vulcanize the rubber portions of the ball and to form an integral construction.

10 The football 31 is formed in a similar manner, the carcass 34 being applied to the inflated bladder 32 after the bladder is covered with suitable rubber cement. The carcass 34 is then coated with rubber cement and the patch layers 38, 38a, 52 and 52a, together with the paper separating layer, are applied to the layer 44. The twisted 15 nylon cord 30 is then wrapped around the inflated football starting at one end of the football and advancing at a substantially uniform rate so that the convolutions are fairly evenly spaced throughout the length of the football. These convolutions extend around the patch layers 38 and engage the outer fabric patch layer 38. After the cord has been tightly wound around the football and cut at the end of the football, the football is coated with rubber cement and the cover layer 33 is applied to cover the football completely. The football may then be molded 20 in the usual manner.

25 The cord 30 may be applied very rapidly prior to application of the cover layer by mounting the inflated unvulcanized football on a mandrel or other machine having means to grip the ends of the football and motor means to rotate the football about its axis. The cord is attached to the football at one end and held under tension during rotation of the football so that it is wrapped around the football, the cord being held at a slight inclination to obtain closely spaced convolutions which extend the length 30 of the football as shown in Fig. 7. The end of the cord is cut after the cord reaches the opposite end of the football. The time required to apply the cord 30 is, therefore, very small and does not add appreciably to the cost of making the football.

35 It is to be understood that, in accordance with the provisions of the patent statutes, variations and modifications of the specific article disclosed herein may be made without departing from the spirit of the invention.

Having described my invention, I claim:

40 1. A molded rubber football comprising an impervious 45 inflatable rubber bladder having an inflation valve, a rubberized fabric carcass enclosing said bladder and bonded thereto, an outer cover coextensive with said carcass and enclosing the same, said cover being disconnected from the carcass within a small area to form a pocket between the cover and the carcass, said cover having flap portions 50 overlying said pocket with two parallel rows of equally spaced lacing holes therethrough of a size to receive the lacing and a slit located midway between and parallel to said rows of holes, the holes of one row being laterally aligned with those of the other row, said flap portions 55 having lacing-supporting ribs of substantially uniform height extending longitudinally substantially the length of said rows at the margins of said slit and parallel to said 60 slit and having transverse trianguloidal lacing-supporting

ribs on opposite sides of said longitudinal ribs aligned with said lacing holes, each transverse rib extending between a lacing hole and a longitudinal rib and having an outer surface spaced radially outwardly from the outer surface of said longitudinal rib a distance corresponding substantially to the thickness of the lacing.

2. A vulcanized molded rubber football comprising an inflatable inner rubber bladder, an enclosing carcass including a layer of rubberized fabric bonded to the outside of said bladder, an outer cover substantially coextensive with said carcass and enclosing the same, said cover being bonded to said carcass except for an area which is small as compared to the total surface area of the carcass so as to form a pocket between the cover and the carcass, the portion of said cover over said pocket being provided with two parallel rows of substantially equally spaced lacing holes therethrough and being provided with a slit therethrough which is located between and parallel to said rows of holes and of a length not substantially less than the length of said rows of holes, the holes of one row being laterally aligned with the holes of the other row, said holes and said slit throughout its length all communicating with said pocket, said cover defining the outer wall of said pocket, a removable lacing threaded through said holes and spanning said slit, said lacing having parallel longitudinal portions adjacent said slit between said rows of holes and parallel transverse portions extending over said longitudinal portions to hold them in place between the lacing holes, and a pair of trianguloidal lateral ribs aligned with each pair of holes on opposite sides of said slit, said ribs projecting radially outwardly from said cover and having outer surfaces substantially flush with the outer surfaces of said longitudinal lacing portions, said transverse portions engaging said ribs substantially from the margins of said holes to the outer side edges of said longitudinal portions.

3. A vulcanized molded rubber football comprising an inflatable inner rubber bladder, an enclosing carcass including a layer of rubberized fabric bonded to the outside of said bladder, an outer cover substantially coextensive with said carcass and enclosing the same, said cover being bonded to said carcass except for an area which is small as compared to the total surface area of the carcass so as to form a pocket between the cover and the carcass, the portion of said cover over said pocket being provided with two parallel rows of substantially equally spaced lacing holes therethrough and being provided with a slit therethrough which is located between and parallel to said rows of holes and of a length not substantially less than the length of said rows of holes, the holes of one row being laterally aligned with the holes of the other rows, said holes and said slit throughout its length all communicating with said pocket, said cover defining the outer wall

of said pocket, a removable lacing threaded through said holes and spanning said slit, said lacing having parallel longitudinal portions adjacent said slit between said rows of holes and parallel transverse portions extending over said longitudinal portions, a pair of longitudinal ribs of the same height below said longitudinal lacing portions on opposite sides of said slit for supporting said longitudinal lacing portions, and a series of lateral ribs projecting outwardly from said longitudinal ribs toward the adjacent lacing holes, said lateral ribs having a height at the sides of the longitudinal ribs substantially greater than that of the longitudinal ribs to provide recesses of a size to receive the two longitudinal lacing portions and engaging the transverse lacing portions to provide support therefor.

4. A molded rubber football comprising an impervious inflatable rubber bladder having an inflation valve, a rubberized fabric carcass enclosing said bladder and bonded thereto, an outer cover coextensive with said carcass and enclosing the same, said cover being disconnected from the carcass within a small area to form a pocket between the cover and the carcass, said cover having flap portions overlying said pocket with two parallel rows of equally spaced lacing holes therethrough of a size to receive the lacing and a wide longitudinal lacing-supporting rib having a width greater than its height located midway between and parallel to said row of holes and extending substantially the length of said rows, the holes of one row being laterally aligned with those of the other row, said flap portions having lacing holes at the opposite ends of said longitudinal rib of a size to receive the lacing and narrow transverse lacing-supporting ribs on opposite sides of said wide rib integral with said rib and aligned with said lacing holes, each transverse rib extending between said wide rib and a lacing hole of one of said rows and having an outer lacing-engaging surface extending radially outwardly beyond the outer lacing-engaging surface of said wide rib to provide a lacing-engaging shoulder at the side of said wide rib.

5. A football as defined in claim 1 wherein a reinforcing cord is embedded in the rubber portion of said football to prevent bulging of the football at the lacing, said cord being wrapped around the football to provide a multiplicity of closely spaced convolutions extending substantially the length of the football and located at the inner surface of said cover and radially outwardly of said pocket, said cord being cut at said slit.
